United States Patent Office

Des. 228,934

Patented Oct. 30, 1973

228,934

POT FOR PLANTS AND THE LIKE

Frank E. Humphries, 1128 26th Ave., Apt. 104, Greeley,
Colo. 80631, and Milford H. Brinkerhoff, 15 Sunset
Drive, Englewood, Colo. 80110

Filed Oct. 6, 1972, Ser. No. 291,070

Term of patent 14 years

Int. Cl. D11—02

U.S. Cl. D35—3 A

FIG. 1 is a perspective view of a pot for plants and the like showing our new design;

FIGS. 2, 3 and 4 are side elevational views thereof;

FIG. 5 is a top plan view thereof; and

FIG. 6 is a bottom plan view thereof.

We claim:

The ornamental design for a pot for plants and the like, as shown.
